Primary Examiner — Susan Bennett Hattan*Assistant Examiner* — Suzanne E Tisdell(74) *Attorney, Agent, or Firm* — Haynes and Boone, LLP(57) **CLAIM**

The ornamental design for a front valence, as shown and described.

DESCRIPTION

FIG. 1 is a perspective view of a front valence.

FIG. 2 is a front elevational view of the front valence of FIG. 1.

FIG. 3 is a back elevational view of the front valence of FIG. 1.

FIG. 4 is a side elevational view of the front valence of FIG. 1.

FIG. 5 is a side elevational view of the front valence of FIG. 1 from the other side compared to FIG. 4.

FIG. 6 is a top plan view of the front valence of FIG. 1.

FIG. 7 is a bottom plan view of the front valence of FIG. 1; and,

FIG. 8 is a perspective view of the front valence of FIG. 1 sitting within a semi-truck cab.

The items shown with broken lines form no part of the claimed design.
